(57) **CLAIM**

The ornamental design for a textile bandage for immobilizing support of the thumb, as shown and described.

DESCRIPTION

FIG. 1 is a top plan view of a textile bandage for immobilizing support of the thumb according to my new design.

FIG. 2 is a top plan view showing the textile bandage in a folded configuration.

FIG. 3 is a side view showing the textile bandage in a wrapped configuration.

FIG. 4 is another side view, opposite the view of FIG. 3, showing the textile bandage in a wrapped configuration; and,

FIG. 5 is a bottom view showing the textile bandage in a wrapped configuration.

The dashed lines shown directly on the surface of the claimed article, in FIGS. 2, 3 and 4, are understood to represent stitching.
